UNITED STATES PATENT OFFICE.

JOHN D. LAWRENCE AND WILLIAM C. LAWRENCE, OF NEW YORK, N. Y.

CURRY-COMB.

SPECIFICATION forming part of Letters Patent No. 276,696, dated May 1, 1883.

Application filed January 10, 1883. (No model.)

To all whom it may concern:

Be it known that we, JOHN D. LAWRENCE and WILLIAM C. LAWRENCE, of the city, county, and State of New York, have invented certain 5 Improvements in Curry-Combs, of which the following is a specification.

Our invention relates to that class of curry-combs constructed to afford a rest to the hand above the comb-bars; and it consists in constructing the back of the comb, as fully described hereinafter, so as to serve to connect the comb-bars, afford the desired rest, and secure both the advantages of open and closed back combs.

15 In the drawings, Figure 1 is a plan view of a curry-comb embodying our invention. Fig. 2 is a side view. Fig. 3 is a perspective view of the back detached. Fig. 4 is a front edge view of the back. Fig. 5 is a section on the line 1 2, Fig. 4. Fig. 6 is the same as Fig. 5, showing a modification; and Fig. 7 is a section of the back plate, showing another modification.

The comb may be of any suitable construction, consisting, for instance, of toothed bars *a*, assembled and connected in the usual manner; knocker-plate *b*, side handle, *A*, and mane-comb *B*.

30 The back plate, *C*, of the comb, instead of lying flat upon the comb-bars throughout its whole extent, as is usual in closed-back combs, is bent or stamped up at the center, so as to form a bridge, *d*, inclosing a small space, *x*, above the comb-bars, and to the top of which 35 is riveted or otherwise secured a plate, *f*, which is prolonged to form the tang upon which to drive the handle *A*. The back plate, as thus constructed, serves as a means of connecting together the comb-bars and supporting the 40 knocker-plates, and also as a support for the handle in an elevated position above the back, without the use of the usual bent shanks or connecting-wires, while the space *x* receives the combings which can escape through the 45 front opening, that the bars may be cleaned in the same manner as an open-backed comb, yet the covering of the back secures all the advantages of a closed-back comb. At the same time the bridge or elevated portion *d* affords a rest for the palm of the hand, so that

the latter can be spread over the comb in a comfortable position. To facilitate the grasping of the comb in the manner last indicated, a thumb-rest underneath the side handle may be secured either by bending in a portion of 55 the metal at *y*, as shown in Fig. 5, or by riveting on an additional piece, *g*, to close the rear end of the opening covered by the bridge, as shown in Fig. 6.

In Figs. 1 to 6 the sides of the bridge di- 60 verge and increase in height toward the rear, so as to incline the top of the bridge toward the front downward, a portion of the metal being turned up or down at the front edge to form a stiffening-rib, *e*. 65

The bridge, instead of having flat sides, may be arched, as shown in Fig. 7, and may be cut away at points, so as to reduce the weight, and it may be inclined to meet the front bar, so as not to leave any front opening, as shown in 70 dotted lines, Fig. 2.

To facilitate the holding of the comb when the hand is spread over the back, we extend a blade or horn, *h*, upward from a point near the inner end of the side handle, *A*. The hand 75 may be extended over the back with the horn between the forefinger and middle finger, and with the thumb against the thumb-rest at *y*, when the comb can be easily and securely held.

We are aware that continuous handles have 80 been applied to extend over the backs of combs; but our back plate is not in any sense a handle, but is continuous and imperforate, forming a closed back.

We claim—

1. A curry-comb, provided with a continuous back plate bent upward to form a bridge or arch, and with a side handle connected to the said bridge, substantially as set forth.

2. A curry-comb provided with a side handle 90 and with comb-bars, and with a continuous back plate elevated to form a central space, *x*, above the bars, substantially as set forth.

3. The combination, with the bars and side handle of a curry-comb, of a continuous back 95 plate raised to form a space, *x*, closed at the rear to constitute a rest for the thumb, substantially as set forth.

4. The combination, with the bars and handle of a curry-comb, of a continuous back plate 100

bent upward to form a bridge, narrow and elevated at the rear and expanded and inclined downward toward the front, as specified.

5. The combination of the comb-bars, inclined continuous back, side handle, and blade *h*, projecting upward from the end of the side handle, substantially as set forth.

In testimony whereof we have signed our

names to this specification in the presence of two subscribing witnesses.
